SWITCH STAND

Paul Hoffman, La Grange, and Whittier Perdue,
Chicago, Ill., assignors to Ramapo Ajax Cor-
poration, New York, N. Y., a corporation of New
York

Application April 3, 1935, Serial No. 14,382

5 Claims. (Cl. 246—411)

The invention relates to railroad switch stands, and more particularly to switch stands of the so-called gearless type.

According to a preferred embodiment of the invention, the switch stand is provided with a spindle having the usual operating arm for attachment to the switch points. A crank shaft is provided whose crank pin is disposed at an acute angle with the axis of the shaft. This crank pin is journaled in a disc which in turn is journaled in a rectangular slot passing through the spindle. The hand lever for operating the switch point is connected by a lost motion connection to the crank shaft. The angle of the crank pin with the crank shaft is sufficiently greater than 45° that the spindle may be rotated its full 90° operating range without requiring the crank pin to be operated between full dead center positions. The lost motion connection permits a full 180° throw of the hand lever from one horizontal position to the other, while permitting less than 180° throw to the crank shaft.

Such a switch stand overcomes the disadvantages of the switch stand disclosed by Perdue Patent No. 1,526,561, patented February 17, 1925, while retaining all of the advantages inherent in this type of stand. The full thrown positions of the crank pin in the present switch stand falling short of dead center avoids setting up great stresses approaching infinity, a condition sometimes obtained in the old type of switch stand disclosed in the above mentioned patent, when the switch was out of adjustment. At the same time the thrown positions of the crank pin in the present switch stand are sufficiently close to dead center to obtain the desired non-reversibility so that stresses exerted on the switch points by the rolling stock in normal operation cannot operate the switch stand. At the same time the full 90° movement of the spindle as required for the target is retained. The full 180° throw of the hand lever is also retained so that it lies flat and out of the way in each thrown position and allows the switchmen to step on the hand lever.

The invention also consists in certain new and original features of construction and combinations of parts hereinafter set forth and claimed.

Although the novel features which are believed to be characteristic of this invention will be particularly pointed out in the claims appended here-

to, the invention itself, as to its objects and advantages, and the manner in which it may be carried out, may be better understood by referring to the following description taken in connection with the accompanying drawings forming a part thereof, in which

Fig. 1 is a plan view illustrating the new switch stand attached to a switch;

Fig. 2 is an elevation of the switch stand taken on the line 2—2 of Fig. 1;

Fig. 3 is a top plan view of the switch stand with the horizontal cover removed and with parts broken away;

Fig. 4 is a section on the line 4—4 of Fig. 3;

Figs. 5 and 6 are fragmentary sections on the lines 5—5 and 6—6, respectively, of Fig. 3;

Fig. 7 is a plan view of the crank shaft.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, one stock rail of the railway switch is illustrated by 10 and one switch point of the switch is illustrated by 11. The switch rod 14 connects switch point 11 to the other switch point (not shown) as will be understood by those skilled in the art. The rails 10 and 11 rest on tie plates 12 which in turn rest on the elongated ties 13 which also support the switch stand denoted by 16. The usual connecting rod 15 pivotally connects switch rod 14 to the operating arm 25 (Figs. 1, 2, 3 and 4).

It will be understood that the switch stand 16 may be used with a switch of any desired or conventional construction and that the present switch is shown only for purposes of illustration. Furthermore, it will be understood that the switch stand may be used to operate other track points, for example, derailing switches, movable point frogs, etc.

The switch stand 16 comprises a casing 11 and

closing the operating parts. The casing 17 is made up of a body 18 and a detachable cover 19. The body 18 has an enlarged base which is bolted to the railroad ties 13 in the usual manner. The cover 19 is detachable from the body 18 by the bolts 50 in the usual manner.

Journalled within the casing 17 is a vertical spindle 20 supporting the usual target 21 and having journal portions 22 and 23 cooperating with bearings in the body 18 and cover 19 respectively (Figs. 4, 5 and 6). Intermediate the journals 22 and 23 is an enlarged portion comprising side plates 24 forming a recess therebetween for receiving a flat disc 33 for a purpose hereinafter described more in detail.

The bottom of the spindle 20 has the usual switch operating arm 25 having a screw threaded adjustable connection 26 with the spindle 20. The end of the operating arm 25 is connected to the connecting rod 15 by the usual pivot connection 27.

For operating the spindle 20 crank shaft 28 is provided. This crank shaft has a journal portion 29 journalled between the cover 19 and body 18, being retained in position by suitable shoulders, as indicated in Figs. 3 and 7. The crank shaft 28 has a crank or overhung portion 30 which carries a crank pin 31. It will be noted particularly from Fig. 7 that the angle between the axis of the crank shaft 28 and the crank pin 31 is 51°. The angle between the crank 30 and the axis of the crank shaft is 45°, while the angle between crank 30 and the crank pin 31 is 84°. The reasons for these angles will be apparent as the description proceeds. It will be understood that the invention is not limited to these particular angles, but other angles may be used so long as the principle of the invention is followed.

For connecting the crank shaft 28 to the spindle 20, a flat disc 33 is provided, this disc having flat sides cooperating with the flat sides of the side plates 24 and having a bearing opening 32 in which the crank pin 31 is journalled. A suitable washer and cotter pin, identified by 51, insures the maintenance of the disc 33 in proper position on the crank pin 31.

For operating the crank shaft 28, a hand lever 34 is provided having the usual weight 35 at the end thereof. To throw the switch this hand lever is moved from one horizontal position, as shown for example in Fig. 2, to the other horizontal position, in both cases engaging stops 36 as will be understood by those skilled in the art.

To obtain a limited lost motion between the hand lever 34 and the crank shaft 28, the former is provided with a bearing 37 journalled on a journal portion 38 of the crank shaft 28. A suitable nut which may be locked by a suitable cotter pin holds the hand lever 34 in proper axial position.

For limiting the lost motion movement between hand lever 34 and crank shaft 28, the bearing 37 is provided with a housing having a pair of abutments 40 which cooperate with a pair of abutments 41 on the crank shaft 28 (Fig. 2). The angle between the abutments 40 and 41 is such as to give, in the form shown, a lost motion of 60°.

The switch points and the switch stand are shown in Figs. 1 and 2 to be in one thrown position. To operate the switch point 11 to cause it to engage the stock rail 10, the hand lever 34 is raised, the abutments or stops 40 and 41 engaging after stops 40 move an angle of 60°. Fur-

ther movement of the hand lever 34 toward the other horizontal thrown position causes rotation of the crank shaft 28, moving the crank pin 31 from the full line position in Fig. 6 to the dot-dash line position in Fig. 6. As the crank pin 31 takes the dot-dash position in Fig. 6, the hand lever 34 engages the right hand stop 36 in Fig. 2. Thus, while the hand lever 34 moves 180°, the crank pin 31 moves only 120°.

As the crank pin 31 moves from one thrown position to the other, it rotates within the disc 33 at the same time the disc 33 rotates within the side plates 24. The angles of the crank shaft illustrated in Fig. 7 are such that this movement of the crank pin 31 causes the spindle 20 to rotate the standard 90° required by the target 21 which has the usual 90° presentations. It will be understood that to move the switch point 11 back to the other thrown position shown in Fig. 1, the hand lever 34 will be moved from its right hand horizontal position in Fig. 2 to the position illustrated in Fig. 1, repeating the sequence of events just described.

Thus, a switch stand has been described which has all of the advantages of the switch stand disclosed in the above mentioned Perdue patent. The switch stand is of great simplicity, there being a minimum number of wearing parts. The parts do not have to be closely fitted and they may be assembled with a minimum of ease. At the same time the disadvantages of prior art stands are overcome in that there are no dead center positions for the crank pin 31. Thus, the setting up of almost infinite stresses on the switch stand, the switch points and connecting apparatus due to dead center positions of the crank pin is avoided.

At the same time, the advantages of a 90° movement of the spindle 20 and the advantages of a full 180° movement of the hand lever 34 are retained. The thrown positions of the hand lever are horizontal so that the hand lever will be down and out of the way and the switchmen can step on it to close the switch for the latter part of the closing stroke.

While certain novel features of the invention have been disclosed and are pointed out in the annexed claims, it will be understood that various omissions, substitutions and changes may be made by those skilled in the art without departing from the spirit of the invention.

What is claimed is:

1. In a switch stand, a casing, a crank shaft within said casing having a crank pin which has an angle of more than 45° with the crank shaft, a spindle journalled in said casing, said spindle having an arm for connection to the rail point to be operated, said spindle having a seat, a member journalled in said seat, said member being journalled on said crank pin, a hand lever having a lost motion connection with said crank shaft, rests for limiting the thrown positions of said hand lever, whereby, when said hand lever is operated from one horizontal position to the other, said spindle is moved through substantially 90° and said crank pin falls short of dead center in each thrown position.

2. In a switch stand, a support, a crank shaft journalled therein and having a crank pin which has an angle of more than 45° with the crank shaft, a spindle journalled in said support and operated by said crank pin, the axes of said crank shaft and spindle intersecting at right angles, said spindle having a member for connection to the rail point to be operated, a hand lever having a

lost motion connection with said crank shaft to operate the switch stand, and means for limiting the thrown positions of said hand lever to horizontal, the angle of said crank pin and said lost motion connection being such that, when said hand lever is operated from one horizontal position to the other, said spindle is moved through substantially 90° and said crank pin falls short of dead center in each thrown position.

10 3. In a switch stand, a support, a crank shaft journaled on said support having a crank pin which has an acute angle with said crank shaft of more than 45° , a spindle journaled in said support, said spindle having means for connection 15 to the rail point to be operated, said spindle having a recess, a disk journaled in said recess, said disk being journaled on said crank pin, a hand lever connected to said crank shaft, and means whereby, when said hand lever is operated from 20 one thrown position to the other, said crank pin falls short of dead center in each thrown position.

4. In a switch stand, a support, a crank shaft journaled on said support having a crank pin which has an acute angle with said crank shaft of more than 45° , a vertical spindle journaled on 25 said support, said spindle having a crank arm for connection to the rail point to be operated, said

spindle having a recess, a disk journaled in said recess, said disk being journaled on said crank pin, a hand lever having a lost motion connection with said crank shaft, said acute angle and said lost motion being such that, when said hand lever is operated from one horizontal position to the other, said spindle is moved through substantially 90° and said crank pin falls short of dead center in each thrown position.

5. In a switch stand, a casing, a crank shaft 10 within said casing having a crank pin which has an angle of the order of 51° with said crank shaft, a vertical spindle journaled in said casing, said spindle having an arm on its lower end for connection to the rail point to be operated, said 15 spindle having a recess, a disk journaled in said recess, said disk being journaled on said crank pin, a hand lever having a lost motion connection with said crank shaft, said lost motion connection being of the order of 60° whereby, when said 20 hand lever is operated from one horizontal position to the other, said spindle is moved through substantially 90° and said crank pin falls short of dead center in each thrown position.
